UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Original application filed September 21, 1916, Serial No. 121,377. Divided and this application filed April 13, 1922, Serial No. 554,776. Renewed October 6, 1923.

My invention relates to railway signaling, and particularly to signaling of the type in which alternating current is employed in the track rails for the purpose of controlling traffic thereover.

The present application is a division of my co-pending application filed on the 21st day of September 1916, Serial No. 121,377, for railway signaling.

10 I will now describe certain forms of signaling systems and apparatus embodying my invention, and will then point out the novel features thereof in claims.

In the accompanying drawing, Fig. 1 is a diagrammatic view showing one form of signaling apparatus embodying my invention. Fig. 2 is a diagrammatic view showing a modified arrangement of apparatus also embodying my invention. Fig. 3 is a 20 view showing a modified form of vehicle receiving circuit which may be employed instead of the circuits shown in Figs. 1 and 2. Fig. 4 is a diagrammatic view showing one arrangement of speed governing apparatus which may be employed in conjunction with the relays shown on the vehicle in Figs. 1 and 2.

Similar reference characters refer to similar parts in each of the several views.

30 Referring first to Fig. 1, the reference characters H and H' designate the track rails of a railway along which cars or trains normally move in the direction indicated by the arrow. The railway is divided into block sections A—B, B—C, etc., by any suitable means which, as here shown, are insulated joints 2 in the rail H'. The other rail H being electrically continuous it may, if the propulsion energy for the cars is electricity, be included in the circuit for the propulsion current in the usual or well known manner. It is immaterial to the present invention, however, how the segregation of the block sections is accomplished, and whether or not the car propulsion energy is electricity, and if so, whether it is direct or alternating current.

For each block section I provide means for impressing on the rails thereof signaling currents differing in frequency. As here shown, two such currents are employed, and they are supplied from two pairs of transmission mains 3 and 3^a, which pairs are connected respectively with two generators

4 and 4^a of alternating currents differing in frequency.

The two pairs of transmission mains 3 and 3^a are alternately connected with the track rails of the successive sections by means of transformers T and T', so that the rails of any one section are directly supplied with current of one frequency only. The primary of each transformer is connected with one of the transmission mains 3 and 3^a, and the secondary is connected with the track rails of the corresponding section adjacent the exit end thereof. Connected in series with the primary of each transformer T is a condenser 5 which serves to balance the reactance of the circuit and thus to reduce to a minimum the impedance of the circuit to current of the frequency of generator 4; that is, the primary circuit of transformer T is tuned to resonance. Similarly, a condenser 5^a is connected in series with the primary of each transformer T' in order to reduce to a minimum the impedance of this circuit to current of the frequency of generator 4^a. The secondary of each transformer T is connected directly across the rails, and included in series with such secondary is a condenser 6 which forms with the secondary winding a circuit resonant to the frequency of the current supplied to the primary of this transformer. The secondary of each transformer T' is also provided with a condenser 6^a to form a circuit resonant at the frequency supplied by the primary of this transformer.

In order to secure currents of both frequencies in each section, I provide resonant transformer bonds N and N^a connected around the rail joints 2, each bond comprising a transformer whose primary is connected with the two adjacent sections of rail H' and whose secondary is connected with a condenser as shown. Each of these bonds is adjusted to resonate at the frequency of the current which is directly supplied to the forward of the two sections to which the bond is connected; that is, bond 100 N^a at location B is resonant at the frequency of generator 4^a, bond N at location C is resonant at the frequency of generator 4, etc. It will be seen, therefore, that normally the current which is directly supplied to each section is freely transmitted to the section next in the rear, but cannot reach the second section in the rear because it is

intercepted by a bond which offers a relatively high impedance to current of that frequency.

Located adjacent the entrance end of each block section is a relay S adapted to respond to current of the frequency supplied to the rails by transformer T . This relay is connected in a circuit including the secondary of a step-up transformer 7 and a condenser 8 , which circuit is tuned to resonance at the frequency of the current delivered by transformer T . The primary of transformer 7 is connected across the track rails of the section, and in series therewith is a condenser 9 , this condenser and the transformer primary forming a circuit tuned to resonance at the frequency of the current delivered by transformer T . Also located adjacent the entrance end of each section is a second relay S' responsive to the current supplied by generator 4^a and transformer T' . This relay is connected with the track rails in the same manner as relay S , except that the circuit comprising condenser 8^a and the secondary of transformer 7^a , and the circuit comprising the primary of this transformer and condenser 9^a , are resonant to current of the frequency delivered by generator 4^a and transformer T' .

Inasmuch as relays S and S' are connected with the track rails through the medium of circuits resonant to the frequencies of transformers T and T' respectively, it is obvious that these relays will respond selectively to currents of these two frequencies, that is, neither relay will be energized unless current of the frequency to which its associated circuits are tuned is present. It will be evident, therefore, that when a block section is occupied by a car or train, both relays connected with that section will be de-energized, and only one relay for the section in the rear will be energized depending on which frequency is directly supplied to such section in the rear.

In Fig. 1, each block section is provided with a fixed or roadside signal F , located adjacent the entrance end of the section. As here shown each of these signals is of the well known "light" type comprising three electric lamps G , Y and R , indicating, when illuminated, "proceed", "caution" and "stop", respectively. These several indications are usually conveyed by green, yellow and red glasses in front of the lamps, as is well understood in the art. These lamps are controlled by the associated relays S and S' through the medium of circuits supplied with current from a suitable source such as a battery 11 . These circuits need not be traced in detail, it being sufficient to point out that lamp G is controlled by the upper point of contact 12 of relay S and the upper point of contact 13 of relay S' so that this lamp can be illuminated only when both relays are energized, that is, when the corresponding block section and the section next in advance are unoccupied; lamp Y is controlled by the upper point of contact 12 of relay S and the lower point of contact 13 of relay S' , or by the upper point of contact 13^a of relay S' and the lower point of contact 12 of relay S , so that this lamp is illuminated when either relay is energized and the other relay is de-energized, that is, when the corresponding block section is unoccupied and the section next in advance is occupied; and lamp R is controlled by the lower point of contact 12 of relay S and the lower point of contact 13^a of relay S' so that this lamp is illuminated only when both relays are de-energized, that is, when the corresponding section is occupied by a car or train. It is believed that the operation of these signal circuits will be obvious from the foregoing explanation, so that no further detailed discussion is required.

At the left of the drawing I have shown diagrammatically a railway vehicle V (a car, locomotive or train) which is equipped with apparatus adapted to be controlled by the signaling currents in the track rails and which apparatus is arranged to give signal indications by virtue of which the speed or progress of the vehicle are governed. As here shown, the signaling apparatus comprises three lamps, G' , Y' , and R' , which lamps are used to give the same indications as those in the roadside signals, viz, "proceed", "caution" and "stop" respectively. The signal lamps on the vehicle are controlled by two relays P and P' also carried on the vehicle, and this control is exactly the same as the control of the lamps in the roadside signals by the associated roadside relays S and S' . The relays P and P' are responsive to the signaling currents, and are controlled by these currents in the manner which I will now explain.

Mounted on the vehicle V in front of the forward pair of wheels is a coil 14 which is in inductive relation to the forward axle and to a short section of both of the track rails in advance of that axle. Across the terminals of coil 14 is connected a condenser 15 , coil 14 and condenser 15 comprising a closed receiving circuit a tuned to the frequencies of both signaling currents in the track rails.

Inasmuch as the currents which flow in this receiving circuit are very feeble and are therefore unsuitable to operate relays constructed with sufficient ruggedness for commercial purposes, I interpose between the circuit and the relays a current amplifying device K , which I will now describe.

The amplifying device K comprises a vacuum tube or bulb 16 having mounted therein a filament 17 , preferably of tungsten, a metallic plate, and a metallic grid 18 interposed between the filament and the plate. The filament 17 is constantly heated

by a battery 20, and the terminals of condenser 15 are connected by wires 21 and 22, respectively with the grid 18 and the filament 17 so that the alternating currents in the receiving circuit *a* produce an alternating difference of potential on the grid. A battery 23 is connected with the filament 17 and the plate 19 in such direction that current therefrom will flow through the tube 10 or bulb K owing to the electron emission from the heated filament 17. The oscillating difference in potential on grid 18 serves to increase and decrease the rate of emission of electrons from the filament and hence produces corresponding variations in the strength of current flowing in the circuit of battery 23. The circuit of battery 23 includes the primaries of transformers 25 and 25^a across the terminals of which is connected a condenser 24 to tune the transformer circuit to the frequencies of the two signaling currents. The secondaries of these transformers 25 and 25^a are connected with relays P and P' respectively by means of circuits made resonant to the two signaling frequencies respectively by condensers 26 and 26^a, as shown. The variations in the strength of the current from battery 23 are thus reproduced as alternations in the resonant relay circuits, and so in the windings of the relays themselves.

The operation of the system shown in Fig. 1, so far as the fixed roadside signal F is concerned, will be readily understood and may be briefly explained as follows:

When a section such as D—E is occupied by a vehicle V', the red lamp R of the signal for that section is illuminated because both relays S and S' for the section are de-energized; the signal therefore indicates stop. As for section C—D, relay S is energized by the transformer T for this section, but relay S' is de-energized, current for this relay from transformer T' for section D—E, which transformer is not shown, being cut off by vehicle V'; signal F for section C—D consequently indicates "caution". The green lamp G of the signal for section B—C is illuminated because both relays S and S' for this section are energized; the signal E for this section, therefore, indicates "proceed".

The operation of the vehicle carried signaling apparatus is as follows:

When the vehicle V is in section A—B, which section is unoccupied except for vehicle V, both relays P and P' on this vehicle are energized so that the green lamp G' is illuminated, indicating "proceed". As the vehicle enters section B—C, no change will occur because this section and the section C—D in advance are unoccupied. When, however, the vehicle enters section C—D, which is the section in the rear of an occupied section, relay P' will become de-energized because the signaling current from generator 4^a to which this relay responds is not present in the rails of the section; lamp G' will therefore, be extinguished and lamp Y will become illuminated so that the signal on the vehicle will indicate "caution". As the vehicle V enters section D—E which is already occupied by vehicle V', relay P will also become de-energized because of the absence of signaling current in the rails of this section, so that lamp Y' will become extinguished and lamp R' will be illuminated, indicating "stop".

The signaling system shown in Fig. 2 is similar to that shown in Fig. 4 in that identical means are employed for impressing the signaling currents upon the rails of each block section and that signaling currents of both frequencies are obtained in each block section by bridging the insulated joints 2 of each section; in Fig. 2, however, the devices for bridging the joints are bonds M and M^a, each comprising an impedance coil 49 and a condenser 50 which are arranged connected in series around the joint. Each bond M and M^a is resonant to the frequency of the current which is directly supplied to the forward of the two sections as in the form shown in Fig. 1, whereby the current which normally is directly supplied to each section is freely transmitted to the section next in the rear, but cannot reach the second section in the rear because it is intercepted by a bond which offers a relatively high impedance to current of that frequency.

It will be noted that the system disclosed in Fig. 2 is without the roadside signals shown in Fig. 1, the purpose of this omission being to avoid complexity of description. It is apparent, however, that the roadside signals may be used with this system as well as with the system of Fig. 1, and that they may be omitted in either system.

The signaling apparatus on the vehicle V of Fig. 2 is similar to that shown in Fig. 1, except that in lieu of amplifying the currents for both relays P and P' by a single amplifier K, two separate amplifiers K and K' are provided for the two signaling currents, respectively. In this instance the receiving circuit, which is here designated *a'*, comprises the coil 14, wires 21 and 22, condenser 15 and the primaries 51 and 51^a of transformers J and J', and this circuit is tuned to resonance at both of the signaling frequencies. The secondary 52 of transformer J is provided with a circuit which includes a condenser 53 and this circuit is tuned sharply to resonance at the frequency of generator 4. Similarly, the secondary 52^a of transformer J' is provided with a circuit including a condenser 53^a, which circuit is tuned sharply to resonance at the frequency of generator 4^a. The terminals of

condenser 53 are connected with the filament and grid, respectively, of the amplifier K, whereas the terminals of condenser 53^a are connected with the filament and grid, respectively, of amplifier K'. The plate circuit of amplifier K includes the primary of a transformer 25 across the terminal of which is connected a condenser 24 to tune the transformer to resonance at the frequency of generator 4. The secondary of transformer 25 is connected with relay P by means of a circuit which includes a condenser 26, and this circuit is tuned sharply to resonance at the frequency of generator 4. The plate circuit for amplifier K' is similar to the plate circuit for amplifier K, and the secondary circuit for transformer 25^a is similar to the corresponding circuit for transformer 25, except that it is tuned sharply to resonance at the frequency of generator 4^a. It will be seen, therefore, that relay P responds only to current from generator 4, whereas relay P' responds only to current from generator 4^a.

25 The operation of the apparatus shown in Fig. 2, in so far as relays P and P' and the signal lamps G', Y' and R' are concerned, is identical to the operation of the apparatus shown in Fig. 1, and, consequently, further explanation would be superfluous.

Referring now to Fig. 3, I have here shown an alternative means for transmitting energy from the track rails to the apparatus on the vehicle. In this modification the receiving circuit, which is here designated a², is connected directly with the journal boxes or wheels of the front axle of the vehicle and the inductance of this axle is balanced by the condenser 15, so that the circuit is 35 resonant to both of the signaling currents.

It is of course, understood that the relays P and P' on the vehicle in either Fig. 1 or 2 may be employed to give signals of any desired character or to control the vehicle in 45 any desired manner. If it is desirable to govern the speed of the vehicle in accordance with traffic conditions in advance, such control may be accomplished by means such as that shown in Fig. 4, wherein 27 is a contact arm operatively connected with a speed responsive device Q which is in turn driven by a wheel of the vehicle, so that the position of this arm varies with variations in the speed of the vehicle; the higher the speed, 50 the farther this arm swings to the right, and vice versa. This arm co-operates with fixed contact segments 28, 29 and 30, which are included in circuits governed by the contacts of relays P and P', and a brake application magnet M is controlled by these circuits in the following manner. When both relays P and P' are energized, the circuit for magnet M is completed through the upper points of contacts 32 and 33 and the fixed contact segment 28, which is of such length that the

vehicle may then proceed at maximum speed before the circuit will be opened by the movement of arm 27 beyond the right hand end of segment 28. When, however, relay P' becomes de-energized and relay P is energized, 70 this being the caution condition of the vehicle carried apparatus, the circuit for magnet M is completed through the upper point of contact 32 and point of contact 33 of relay P' and segment 29, which segment is 75 shorter than segment 28, so that the vehicle must proceed at an intermediate speed in order to avoid opening the circuit of magnet M. Similarly, when relay P' is energized and relay P de-energized, the circuit for magnet M passes through the lower point of contact 32 and the upper point of contact 33^a and the segment 29. When both relays P and P' are de-energized, this being 80 the stop condition of the apparatus, the circuit for magnet M is completed through the back points of contacts 32 and 33^a and through the very short segment 30, so that if the vehicle exceeds a given low speed, the 85 circuit for magnet M will be opened and the brakes applied. It is understood that so long as magnet M is energized, the brake pipe remains closed and the brakes are not applied. The three speeds corresponding to segments 28, 29 and 30 may be any desired values, such for example, as 60, 30 and 90 10 miles per hour.

Although I have herein shown only a few forms of apparatus embodying my invention, it is understood that various changes 100 and modifications may be made therein within the scope of the appended claims without departing from the spirit and scope of my invention.

Having thus described my invention, what I claim is:

1. A railway signaling system comprising track rails divided into block sections by insulated joints, means for impressing alternating signaling current on the rails of each section, the currents supplied to adjacent sections differing in frequency, resonant bonds connected around the insulated joints each bond being resonant to the frequency of the current supplied to the section in advance but not to the frequency of the current supplied to the section in the rear, and signaling means controlled by said currents in the track rails and selectively responsive to said currents. 110 115 120

2. A railway signaling system comprising track rails divided into block sections by insulated joints, means for impressing alternating signaling current on the rails of each section, the currents supplied to adjacent sections differing in frequency, resonant bonds connected around the insulated joints each bond being resonant to the frequency of the current supplied to the section in advance but not to the frequency of the 125 130

current supplied to the section in the rear, a railway vehicle, and signaling means thereon selectively responsive to said currents in the track rails.

5 3. A railway traffic controlling system comprising track rails divided into block sections by insulated joints, means for impressing signaling current on the rails of each section currents supplied to adjacent sections differing in frequency, resonant bonds connected around the insulated joints, each bond being resonant to the frequency of the current supplied to the section in advance but not to the frequency of the current supplied 10 to the section in the rear, and traffic governing means on a vehicle controlled jointly by said currents in the track rails and by the speed of the vehicle.

15 4. A system of the class described comprising a track divided into blocks, tuned by passes connecting the rails of one block with the rails of a contiguous block, means for impressing an alternating current upon the rails of one block which can not traverse 20 the by-passes at the end of the block signal devices comprising a receiver connected with the rails of said block and responsive to the current aforesaid, said signal devices indicating safety when said responsive means is detecting said current, and indicating danger when said current is short-circuited through the wheels of a car in 25 said block, means for impressing an alternat-

ing current capable of traversing the by-passes aforesaid upon the rails of the contiguous block, and signal devices comprising a receiver connected with the rails of the first block and responsive to current impressed upon the rails of the contiguous block, said last-mentioned signal devices indicating safety when said last-mentioned receiver is detecting the current impressed upon the rails of said contiguous block, and indicating caution when said last-mentioned receiver is not detecting such current. 35 40 45

5. In a system of railway signaling, a track divided into blocks, a danger signal and a caution signal at the entrance into each block, each signal controlled by a receiver tuned to respond to a high frequency current of a certain frequency, by-passes connecting the rails of contiguous blocks, each by-pass tuned to permit a current of a certain frequency to traverse the same, means for impressing upon each block a high frequency current capable of being detected by the receiver associated with the danger signal at the entrance to said block, and means for impressing upon the rails of each block a high frequency current capable of being detected by the receiver associated with the caution signal at the entrance to an adjacent block. 50 55 60

In testimony whereof I affix my signature.
LLOYD V. LEWIS.
